UNITED STATES PATENT OFFICE

2,684,220

RECESSED FLUSH LIGHTING FIXTURE
HANGING BARSamuel L. Beber and Jerome H. Feig,
Los Angeles, Calif.

Application March 11, 1949, Serial No. 80,838

2 Claims. (Cl. 248—27)

1

Heretofore recessed flush lighting fixtures have been formed with flanges welded to the housing as a means of support for the fixture, the flange upon each side of the housing being nailed directly to stringers in the ceiling, or if such stringers are not upon proper centers, then the flanges are secured to a box roughed in and supported by the stringers, and in which the spacing between the flanges and the lip of the housing is such as to provide for a plaster thickness which is constant regardless of the type of construction, and any variation from an assumed thickness of plaster has in the past been compensated for by the insertion of shims and other odd pieces of wood between the flange and the structural support therefore, regardless of whether the support is a stringer or a roughed-in box positioned between the stringers. Obviously this method of installation is slow, expensive, unsightly, unsecure, and, depending upon local ordinances governing electrical installations of this type, cannot be employed in the first instance, whereby one who desires installation of a recessed flush type fixture is deprived of the obvious advantages thereof.

In contra-distinction to the afore-described practice, it is an object of the present invention to provide a simple and readily installed hanger which is adapted by its nature to be attached directly and in positive union with and upon stringers in the ceiling and which hangers permit the housing of the fixture to be vertically adjusted and positioned in accommodation of any thickness of plaster.

An advantage of the invention resides in the fact that a recessed lighting fixture may now be supported in ample clearance with respect to adjacent wood supporting elements whereby free circulation of air is now possible and in mitigation of built-up or accumulated temperature which if unrestricted could attain a point high enough to cause fire.

A further advantage resides in a speed-up of the work involved in an installation of this character with an accompanying decrease in cost.

Another advantage resides in the fact that a recessed fixture supported upon the hanger bars of this invention is more rigidly secured in place, there being no creeping which could possibly chafe the insulation upon the wiring in the circuit with eventual short-circuiting a possibility.

A further advantage resides in the fact that fixtures of the type contemplated may now be adjusted laterally of the hanger bar after the bar

2

has been fixedly secured in position upon a joist, and this fact comprises a definite advantage over previously used means to support a recessed lighting fixture.

Other objects, features and advantages of the invention may be noted from the accompanying drawing, the specification, and the subjoined claims.

In the drawing:

10 Figure 1 is an elevational view showing a recessed flush type lighting fixture positioned between two parallel and adjacent stringers and supported by the hangers of this invention.

15 Figure 2 is an elevational view taken along line 2—2, Figure 1 showing the hanger bars in their adjustable position upon the box of the fixture.

20 Figure 3 is a side-elevational view of one of the hanger bars; and

25 Figure 4 is a front-elevational view thereof; while

Figure 5 is a top-plan view of the hanger bar.

Figure 6 is a sectional view of a portion of the fixture housing, the hanger bar and an adjacent 30 stringer showing detail of construction and adjustability of relationship between the hanger bar and the housing of the fixture.

Figure 7 is a view taken along line 7—7, Figure 2, showing the relationship between the struck-out loop in the box housing and one of the supporting brackets.

35 Figure 8 is a side-elevational view showing a modified form of bracket support adapted to permit lateral movement of the box with respect to the bar after installation of the latter; and

Figure 9 is a top-plan view thereof.

Figure 10 is a top-plan view of the hanger bar shown in Figures 8 and 9; and

Figure 11 is a side-elevational view thereof; while

Figure 12 is an end view of the bar shown in Figures 10 and 11.

Figure 13 is a top-plan view of a further slightly modified form of hanger bar construction; and

45 Figure 14 is an end view thereof.

In the drawing the reference character 10 indicates the box or housing of a recessed flush type of lighting fixture adapted to be supported upon stringers 12 within the ceiling of the room in which the installation is had, and as shown, the fixture is held in fixed relationship to the stringers by means of the hanger bars 14 of this invention. The bars 14 are formed of elongate strips of steel uniform in cross section throughout their lengths, and are bent in substantial

simulation of the letter "L". Each bar has a vertical leg 16 formed with an elongated slot 18 while the horizontal portion or arm 20 is perforated with one or more apertures 22 to receive a nail 24 to be driven into the stringers 12 as a means of securing the hanger bar thereon. A sharply apiced tongue 26 is die struck from the arm 20 and extends parallel with the vertical leg 16 and provides a convenient and rapid means of, first, fixedly centering the hanger upon the stringer, and, secondly, of temporarily securing the hanger upon the stringer by driving it thereinto, prior to driving the nail 24 as shown in Figure 6.

The flanges 28 shown in Figures 1, 2 and 6 are adapted to support a reflector bowl, not shown, and these flanges are placed upon the sides 30 and 32 of the box 10 at right angles to the position of the hanger-bars 14. We provide fastening or mounting means upon the sides 30 and 32 of the box to secure the hanger-bars to the box. The fastening means for each hanger bar involves a loop-shaped ear 34 which is preferably die struck from the side panel of which the box is ultimately formed. The ear is so dimensioned as to readily receive the vertical leg 16 as shown in the several figures of the drawing. We also provide a screw fastener for holding the leg 16. In the case shown the side of the box and the leg have aligned openings receiving a short bolt 36. The opening in the leg extends longitudinally thereof and is in the form of a slot 18.

In Figures 8 to 12 inclusive, we show a modified form of hanger bar for recessed flush lighting fixtures, here the bar has a length in excess of the width of the fixture housing, and as shown the body 20 of the bar 18 is formed with right angled legs 22, being bent at 30 to accomplish this configuration, while each of the legs 22 is bent at 24 to form flanges 26 which are disposed in a plane parallel with the body portion 20. Both the flanges 26 and the body portion 20 have elongated slots 28 formed therein, and which slots are positioned in the hanger bar substantially as shown. The slots 28 in the body 20 being adapted to receive bolts 32 from the housing 10a whereby before being tightened, the housing may be adjusted laterally for centering or other alignment, while the slots 28 in the flanges 26 are adapted to receive and permit a certain amount of adjustment of the fastening means 36 prior to being driven in the joist 12 as shown in Figure 8.

Figures 13 and 14 are illustrative of a slightly modified form of hanger over that shown in Figures 8 to 12, here the slots in the flanges 26 of the hanger bar 18 are formed with open ends whereby a bar may be slid under the head of such a fastening means as the nail 36 after the nail has been centered and partially driven in the joist. The arrangement is advantageous in certain instances of construction, especially where a single workman must perform all tasks involved in an installation, and is likewise of advantage when dismounting a fixture including the hanger bars, for it is not necessary that all of deeply set nails be withdrawn prior to taking the bar down, one such withdrawal will suffice, while the opposite end of the bar is drawn from the nail after having been merely loosened.

The preceding description of our invention is believed to be such as to enable the same to be clearly understood and practiced, and from which it can be seen that regardless of width between centers in the stringers and regardless of the

plaster thickness a recessed flush lighting fixture can be quickly, and easily installed with the simplest of tool and with a minimum understanding of mechanics. In practice the width of centers between stringers is quite standardized but does vary depending upon the degree of permanency of the structure and this applies in like manner to the plaster thickness, but regardless of these considerations, the arm 20 of each of the hanger bars, of which there are four to the installation, is of such length as to span the clearance between the box side and an adjacent stringer, while the position of the box within the ceiling may be vertically adjusted by merely loosening the bolt 36 and raising or lowering the box along the vertical leg 16 to bring the reflector supporting flange into proper alignment with the surface 40 of the plaster 42, substantially as shown in Figure 1, and thereafter tightening the bolt 36 to hold the box 10 in its place of proper adjustment.

The tongue 26 has been found to be advantageous in certain types of construction in facilitating installation, but is not to be considered as a limiting detail of construction of or in the hanger bars, the essence of the invention in which, resides in the provision of means for lateral adjustment of the bar with respect to the supporting stringers and in which means are provided for vertical adjustment of the fixture housing or box with respect to finish line of the plaster or other ceiling surface.

Having thus described our invention in its preferred form, that which we desire to protect by Letters Patent, is:

1. In combination, a box shaped body adjustably related to a wall and having a bottom, sides and ends, a plurality of separately adjustable mounting brackets arranged two at each end of the body and in spaced relation to each other, each bracket being an elongate strap uniform in cross sectional configuration throughout its length and L-shaped in form having an elongate foot portion engaged flat against the body with one end terminating short of the bottom of the body and an arm projecting a substantial distance from the other end of the foot, the foot portions being parallel with each other, and having longitudinal slots therein and releasably engaged in the slots of the foot portion of each bracket to secure the bracket to the end of the body with which it is engaged, the arms being parallel and each arm having a longitudinal series of openings therethrough and extending longitudinally of the arm.

2. In combination, a box shaped body having a bottom, sides and ends, a plurality of separate mounting brackets arranged two at each end of the body and in spaced relation, each bracket being an elongate strap uniform in cross sectional configuration throughout its length and having a foot portion flat against the body and an arm projecting a substantial distance from one end of the foot, the front portion having longitudinal slots therein, and a screw clamp releasably engaged in the slot of the foot portion of each bracket to secure the bracket to the end of the body with which it is engaged, each arm having an anchoring tongue projecting therefrom

intermediate its longitudinal edges and in the same direction that the foot portion is related to the arm and spaced from the foot portion.
